VARIABLE FLOW PULP TREATING MACHINE

John D. Haskell, Fulton, N. Y., assignor to Dilts
Machine Works, Inc., a corporation of New
York

Application January 11, 1934, Serial No. 706,281

1 Claim. (Cl. 92—43)

This invention relates to variable flow pulp treating machines. It is applied customarily in practice to apparatus employed in the manufacture of paper, the pulp being taken up in a web 5 formation by a screening roll or receptacle in a vat charged with pulp and water, the web or sheet being removed from the roll by a couch roll in the common process. The object of this invention is the provision of effective fluid moving 10 means that may be varied so as to alter the amount and velocity of the flow and the deposit upon the screening member in the vat, and the preferred form of such means comprises a propeller wheel located in a suitable conduit termination or connection and having adjustable blades coupled with and operated by attachments extending to the outside of the conduit and which may be arranged by hand. It is not intended, however, to limit this invention to the precise 15 propeller mechanism and combined adjusting contrivances herein illustrated and described, as other means can be substituted by those familiar with the subject. Nor, is it proposed hereby to confine the invention to the web forming type of 20 pulp machines. It may be associated with strain- 25 ers of a variety of constructions, or to other paper treating machines which include a member whereby the pulp or like material is acted upon mechanically as it passes through the machine 30 in a more or less fluent state.

The construction of this invention comprises means for varying the pitch of each blade of a pump impeller while the machine is in operation, the control mechanism being located outside the 35 pump. In this construction the pitch may be varied, that is, increased or decreased to impel more or less water, by means of bevel gears operating through a master bevel pinion operable from the external end of the shaft.

The applicant has found, particularly with paper machine vats where paper of varying weights is made, that considerable difficulty is experienced in handling the correct amount of water for diluting the paper stock, and that a fan pump designed for one weight of paper sheet is not satisfactory for a heavier or lighter weight sheet. This is due to the fact that the pump equipped with a given type impeller efficiently 45 displaces only the amount of water for which the impeller and its speed are designed. It is not uncommon to experience a difference of from 1500 to 3000 gallons per minute, and this cannot be efficiently done in present types of pump designs. With the variable pitch blades, however, it

is possible to instantly change the angle of attack between the impeller blades and the liquid and thereby alter the amount of liquid displaced while the machine is in operation. This application sets forth only one of many methods of accomplishing this variable pitch, and the same effect could be attained by other means, and it would likewise be entirely practical to combine the variable pitch feature with a variable speed 5 motor for driving the pump and which would give added flexibility or adaptability to the apparatus. It will be understood that the water which has passed through the wire net covered cylinder in the vat, is ready to be conducted out of the vat and back at the head box of the machine for diluting the incoming thick pulp. In this way the same water is used over and over again, and the only "make up" water necessary is that which must be added to replace the water which is being carried out by the web of paper.

The accompanying drawings form a part of this application and illustrate the construction and arrangement of the various parts employed. Of the drawings, Fig. 1 represents a side view 25 of the apparatus, all parts being assembled, and showing the connection with a vat and web forming roll and couch roll.

Fig. 2 is a partly sectional side view on a slightly increased scale of drawing, illustrating the conduit entrance, and the adjustable propeller 30 erected therein, with the gear wheels and master gear for effecting the blade adjustment desired.

Fig. 3 is a vertical sectional view of the mechanism for rotating the master gear shaft to alter the pitch of the blades by means of the hand wheel on the external end of the main or drive shaft.

Fig. 4 is a side view similar to Fig. 1 showing the propeller shaft connected with the strainer shaft to rotate the strainer.

Throughout the drawings and description the same number is used to refer to the same part.

In Fig. 1 there is shown erected upon base 1 standards 2 and 3 acting as supports for bearings 4 and 5 of any formation for a drive shaft 6 rotated by a pulley 7, or in any selected manner. The shaft passes through a stuffing box 8 carried by the conduit 9 which has the usual flange 10. The shaft may have a terminal hub 11 carrying the adjustable blades 12 of the impeller, and those blades are adjusted as to pitch by means of the hand wheel 13 and screw shaft 14 at the external end of shaft 6, and as more fully described hereinafter. The flange 10 of the conduit 50

is attached to the casting 15 forming the passage for fluent material from the vat 16. Corresponding in position with the passage through the casting 15 is a hollow cylindrical part 17 forming the communication from the wire covered roll or receptacle 18 with the conduit. The receptacle 18 is carried by the shaft 19 and may have a bearing in a cross member in the casting 15 as shown. The wire covered reticulated roll 18 takes up the pulp in a web in the usual manner, and the web is removed by a couch roll 20. Those parts are variously constructed and arranged in machines for the purpose stated.

As best shown in Fig. 3, the main shaft 6 is hollow, and within the same is the master gear operating shaft 21. In Fig. 2 the master gear 22 on the end of shaft 21 is shown in engagement with the mitre gears 23 and 24. Each mitre gear is attached to the revolvable stem, such as the stem 25 of a propeller blade, the whole being carried by the hollow hub 11 on the end of main shaft 6. Again referring to Fig. 3 there will be noted a circular plate 26 secured by a lock nut 27, or in some other chosen manner, upon the screw shaft 25 by which the plate 26 may be advanced into the hollow of the shaft 6 or withdrawn. The screw shaft engages the threaded end of a suitable bracket support 14' carried by the standard 2. Between the plate 26 and the nut on the inner end of the screw shaft is a ball or roller bearing 28 carried in the outer end of a hollow movable sleeve or block 29 that can be pushed by the operation inwardly or drawn outwardly in the grooved seat 30 formed in the hollow of the main shaft 6. Still considering Fig. 3, it will be observed that the master gear shaft 21 has a projecting cylindrical pin 31 arranged in engagement with a slanting slot 32 in the movable sleeve or block 29.

40 The arrangement illustrated in Fig. 4 is the same as that of Fig. 1 with the exception of the following modification. The drive shaft 33 is revolved by pulley 34, and has at its internal end the propeller with the adjustable blades 35, and at its external extremity the hand wheel 36 on the screw shaft 37, all the same as before. The conduit 38 is attached in a position corresponding with the hollow cylindrical bearing passage 39 of

the strainer 40 carried by vat 41 in revolvable relation. The drive shaft 33 has a terminal 42 having a connection 43 with a like end hub upon the strainer shaft 44. In this construction the strainer 40 is rotated by the drive shaft 33. 5

The operation is the same in either instance and is thought to be readily discernible from the drawings and the foregoing explanation. By means of the hand wheel outside of the vat the sliding slotted member may be moved in or out, 10 and the engagement of the cylindrical pin on the master gear shaft with the slanting slot of the sliding member can be caused to turn the master gear shaft in either direction, and by the action of the gearing alter the pitch of the adjustable 15 blades of the impeller or propeller pump. By the construction and arrangement of the roller bearing at the external end of the main shaft, the screw shaft 14 remains at rest while the main shaft, the master gear shaft and the slotted 20 sliding member rotate together until some desired alteration of the pitch of the impeller blades is required. In this invention as shown and described, the reticulated member in the vat, or other equivalent receptacle may be revolved by 25 the impeller shaft or independently and at a different speed by other rotating means not shown and forming no part of this invention.

Having now described this invention and the 30 manner of its use, I claim:—

In a variable flow pulp treating machine, the combination with a vat, of a strainer in the vat, a shaft adapted to support and revolve the strainer, said strainer and vat having movably 35 communicating conduits through which material may be moved with respect to the interior of the strainer, said conduits being constructed and arranged to permit the revolution of the strainer in the vat, fluid impelling means carried by said shaft comprising a propeller having adjustable 40 blades whereby the flow of material may be varied, said propeller blades revolving with the strainer, means carried by the shaft and connected with the propeller blades for adjusting the blades, and externally located hand operated devices 45 constructed and arranged to control the blade adjusting means.

JOHN D. HASKELL.
